BOX ENDING TOOL

Alfred L. Rosenmund, Rockaway, N. J., assignor
to Stapling Machines Co., a corporation of
Delaware

Application November 8, 1934, Serial No. 752,075

5 Claims. (Cl. 140—117)

This invention relates to tools for securing wired box ends to wired box sides.

It is an object of the invention to provide an efficient and durable tool for securing a wired box end to the sides of a wirebound box.

It is a further object of the invention to provide a tool for engaging a loop or bight on a wire secured to a box end after the loop or bight has been passed through a box side, tension the bight or loop to draw the box end into close contact with the box side and then to bend the hook or bight into hooking engagement with a side binding wire.

Illustrative embodiments of the invention are shown in the accompanying drawings, in which:

Figure 1 is a perspective view of one form of tool embodying the invention.

Figs. 2 and 3 are perspective views of a portion of a wirebound box and a wired end and illustrating the manner in which the tool of this invention is used.

Fig. 4 is a perspective view of a flat wirebound box blank with two end sections secured thereto and illustrating the manner in which the tool of this invention is employed to bend the loops or bights on the box ends preparatory to folding the box blank into box form and inserting the loops or bights on the end sections through the side sections.

Figure 5 is a perspective view of a modified form of tool embodying the invention.

Figs. 6 and 7 are perspective views of a portion of a wirebound box and wired end and showing the manner in which the modified form of tool is used.

Referring to Fig. 1, the tool there shown consists of a handle portion 1 provided with a slot 2 for a purpose hereinafter described. Extending from the handle 1 is a blade 3 having formed on its extremity a hook 4. The lower portion of the blade 3 is formed to provide a cam surface 5 extending backwardly from the extremity of the blade 3.

Referring to Fig. 2, the tool is shown in the position it occupies during the first step in securing a wired box end to a wired box side. As there shown, a box end 6 having wires 7 stapled thereto is in position to be secured to the sides of a wirebound box. The box sides consist of side sheets 8, cleats 9, and binding wires 10. In the illustrative box the side sheets 8 are spaced from each other to provide openings 11. The wires 7 on the box end 6 are provided at their ends with loops or bights 12 which pass through the openings 11 in

the side section and are then passed upwardly between the cleat 9 and the side binding wire 10. When an integral side sheet 8 is used instead of the spaced sheets shown in Fig. 2, the bights or loops 12 are passed through slotted openings provided in the side material, or are passed through grooves formed in the cleats 9.

With the loops or bights 12 in the position shown in Fig. 2, the blade 3 is inserted in the loop 12 with the cam surface 5 resting upon the cleat 9. With the cam surface 5 resting upon the cleat 9, and thus serving as a fulcrum for the extremity of the blade, downward pressure on the handle 1 of the tool will cause the blade 3 to pull the loop or bight 12 upward, thus drawing the end 6 upward, thus drawing the inner sides of the side sheets 8. The tool is then swung from the position shown in Fig. 3 to bend the loop or bight 12 over the side binding wire 10 and down against the side of the box. During this movement of the tool the hook 4 on the extremity of the tool engages under the side binding wire 10, as shown in Fig. 3, the hooking engagement between the end of the tool and the side binding wire 10 serving to position the tool and provide a pivoting point for it during its swinging action.

Referring to Fig. 4, the slot 2 in the handle of the tool 1 may be used to bend the bights 12 to a right angle position relative to the end section 6 so that the bights 12 may be passed between the cleat 9 and the binding wire 10 of the side section when the flat blank is folded into box form. The manner of using the tool for this purpose is illustrated in Fig. 4. The bight 12 is inserted in the slot 2 of the handle of the tool, as shown in full lines. The tool is then swung upward to the position shown in dotted lines, thus bending the bight 12.

In Fig. 5 is shown a modified tool embodying the invention. The tool there shown may be termed a double tool as it carries two spaced blades for engaging and bending two bights simultaneously. As there shown, the pair of blades designated 13 are adjustably fixed to a rod 14 by set screws or other suitable means (not shown). Fixed to the rod 14 and preferably at its center point is a handle 15.

In the modified form of blade shown in Fig. 5, two hooks are formed on the extremity of the blade, an upper hook 16 and a lower hook 17. The upper edge 18 of the blade may be formed to curve slightly upwardly from the hook 16 to facilitate locating the bight 12 in the hook 16. The lower edge 19 of the blade curves downwardly

to serve as a fulcrum for the extremity of the blade for a purpose presently described.

The manner of using the modified double tool is shown in Figs. 6 and 7. Referring to Fig. 6, 5 the upper hooks 16 of the blades 13 engage the bights 12 of the wires on the end sections 6, while the lower edges 19 of the blades rest upon the cleat 9 and thus serve as a fulcrum for the extremities of the blades. Downward pressure on 10 the handle 15 will raise the hooks 16 and draw the bights 12 upwardly between the cleat 9 and the side binding wire 10. After the bights 12 have been raised the blades 13 are inserted 15 through the bights 12 a sufficient distance to permit the lower hooks 17 to engage the side binding wire 10. The handle 15 is then swung down in Fig. 7. This movement hooks the bights 12 over the side binding wire 10, as shown.

20 It will be understood that blades of the form shown in Fig. 1 may be substituted for the form of blade 13 shown in Fig. 5, the upper hook 16 of the blade 13 being desirable for certain operations, but not essential.

25 The blades 13 are adjusted on the rod 14 to accommodate the spacing between bights 12 on the end sections 6.

It will be understood that the invention is not to be limited to the specific embodiment shown 30 for purposes of illustration as the inventive features may be variously embodied.

It will also be understood that all of the features of the invention need not be used conjointly as they may be used in various combinations as 35 defined in the subjoined claims.

I claim:

1. A tool for hooking a wire bight on one box part over a wire on another box part comprising, 40 a handle portion and a blade extending therefrom; the blade at its extremity having a shallow depth and being provided with a hook on each edge, and the blade at a point relatively remote from its extremity having a substantial depth whereby the portion having a substantial depth 45 may serve as a fulcrum for the extremity of the blade.

2. A tool for hooking a wire bight on one box part over another box part comprising, a handle, a rod fixed thereto, and a pair of blades secured to the rod; each blade having an extremity of shallow depth and a portion of substantial depth 5 relatively remote from the extremity, whereby the extremities of the blades may be inserted in wire bights and the portion of substantial depth may be used as a fulcrum for the extremities of the blades.

3. A tool for hooking a wire bight on one box part over another box part comprising, a rod, and a plurality of blades adjustably secured to the rod; each blade having a shallow depth at its extremity and a substantial depth at a point 15 relatively remote from its extremity, whereby the extremity of each blade may be inserted in a wire bight, and the portion of each blade having a substantial depth may serve as a fulcrum for the extremity of the blade.

4. A tool for hooking a wire bight on one box part over a wire on another box part comprising a handle portion and a blade portion; the blade having a shallow depth at its extremity, an upper edge which is substantially level, a lower edge 25 extending from the extremity of the blade at an angle to the upper edge to provide a substantial blade depth at a point relatively remote from the extremity of the blade, and a recess formed in the lower edge adjacent the extremity of the 30 blade to provide a wire-engaging hook.

5. A tool for hooking a wire bight on one box part over a wire on another box part comprising a handle portion and a blade portion; the blade having a shallow depth at its extremity, one edge 35 which is substantially level, another edge extending from the extremity of the blade at an angle to the first-mentioned edge to provide a substantial blade depth at a point relatively remote from the extremity of the blade, and a recess formed 40 in the second-mentioned edge adjacent the extremity of the blade to provide a wire-engaging hook.

ALFRED L. ROSEN MUND.
